LAY GUIDE

Carl D. Brown, Hopedale, Mass., assignor to
Draper Corporation, Hopedale, Mass., a cor-
poration of Maine

Application October 10, 1933, Serial No. 692,983

3 Claims. (Cl. 139—190)

The present invention pertains to looms and has more particular reference to means for guiding the reciprocating lay.

It is usual practice to mount the lay of looms, 5 of the type herein involved, on the upper ends of pivotally mounted lay swords and to swing the lay forwardly and rearwardly about the pivotal axis of such swords. It is of utmost importance that the lay not have any movement laterally 10 of its intended path, and experience has shown that such lateral movement cannot be effectively prevented unless the lay structure is positively guided adjacent the lay. Devices for guiding the lay in the manner indicated have heretofore been 15 devised, reference being had, for example, to Patent No. 775,558, issued Nov. 22, 1904 to W. F. Draper. Such prior devices have been unsatisfactory in that, due to inaccuracies in the loom construction, the guiding means was not always 20 parallel to or in proper position relative to the path of movement of the lay and lay swords.

It is the principal object of my invention to provide a lay guiding means which shall be adjustable in a manner to permit the same to accurately and efficiently guide the lay in its movements.

The preferred embodiment of my invention is illustrated on the accompanying drawing, of which:

30 Fig. 1 is a sectional elevation, looking outwardly toward the right hand side of the loom;

Fig. 2 is a horizontal sectional view, taken approximately on line 2—2 of Fig. 1; and

Fig. 3 is a detail, in perspective.

35 Referring to the drawing, I have fragmentarily illustrated only so much of a loom as is necessary to a complete understanding of my invention. The parts shown include a right hand loom side 1 which is connected with a left hand loom side (not shown) as by a cross-girt 2 and breast beam 3. The lay 4 is mounted, as usual, on lay swords of which only the right hand sword 5 is shown. The swords are pivoted at their lower ends on a rocker shaft 6 which is mounted in 40 bearings as 7 carried by the loom sides. The lay structure thus formed is reciprocated forwardly and rearwardly (the front of the loom being to the right in Fig. 1) by pitman 8.

Since the heavy lay is mounted a considerable 45 distance from the rocker shaft a very little lost motion in the rocker shaft bearings, or a very slight twisting of the lay structure, can permit the lay to move laterally of its proper path sufficiently to impair the operation of the 50 loom. It will be apparent that, due to slight va-

riations in the position of the rocker shaft bearings the path of the lay may not be exactly parallel to the loom side. The lay guide of my invention is constructed to prevent the aforementioned lateral movement of the lay even though the path 60 of the latter be out of parallelism with the loom side.

The lay guide herein disclosed is comprised essentially of two elements having relative sliding movement, one such element being fixed to 65 the loom side and the other being fixed to the contiguous lay sword, and the elements being readily adjustable in a manner to be set forth. The fixed element mentioned is comprised of a flat guide bar 9 which is fixed to the loom side 70 1 adjacent the lay sword 5. The guide bar is positioned in a substantially vertical plane but is capable of adjustment about a vertical axis. In accomplishment of such adjustment, the rearward end of the guide bar is bolted, by bolt 10, 75 against a curved face 11 formed on a lug 12. The lug is conveniently formed separately from the loom side and secured thereto as by bolt 13.

The forward end of the guide bar 9 is apertured to loosely receive a bolt 14 which is fixed 80 in the loom side by a nut 15. Nuts 16, 16 on the bolt serve to rigidly hold the guide bar on the bolt. By loosening the bolt 10 the nuts 16, 16 may be employed to swing the forward end of the guide bar, about a vertical axis, into parallelism with the path of the lay sword 5.

The second element of the lay guide, in the present embodiment, is comprised of a yoke 17 shaped to fit the lay sword, and two separate pieces 18 and 19 in the form of plates positioned 90 on the opposite side of the sword from the yoke 17. A bolt 20 passes through the yoke and through elongated slots 21 and 22 formed, respectively, in the piece 18 and 19. A bolt 23 passes through the yoke and through similar elongated 95 slots 24 and 25 on the opposite side of the sword. The piece 18 has an upwardly extending finger on which is formed a surface 26 which slidably engages the outer vertical side of the guide bar 9, and the piece 19 has a similarly formed but 100 opposed surface 27 which slidably engages the inner vertical side of the guide bar.

The construction just described permits the pieces 18 and 19 to be adjusted together, laterally of the path of movement of the lay sword, 105 and also permits them to be adjusted independently, to conform to the thickness of the guide bar and compensate for wear of the same. Further advantages of the construction are self evident and require no discussion.

Having fully disclosed the preferred embodiment of my invention, I claim:

1. In a loom, the combination of a loom frame, lay and lay swords with a lay guide comprised of a guide element carried by said frame adjacent one of the lay swords, separate pieces having surfaces engaging respectively with opposed surfaces on said guide element, and means securing said pieces to said lay sword for separate, independent adjustment laterally of the path of movement of the lay.
2. In a loom, the combination of a loom frame, lay and lay swords with a lay guide comprised of a guide element carried by said frame adjacent one of the lay swords, a pair of separate plates each of which is provided with a guide finger, which fingers engage respectively with opposite sides of said guide element, a yoke on said lay sword, and clamping bolts passing through said

20

yoke and through horizontal slots in each of said plates for clamping said plates and yokes to the lay sword, the said slots permitting separate, independent adjustment of said plates, and fingers, laterally of the path of movement of the lay.

80

3. In a loom, the combination of a loom frame, lay and lay swords with a lay guide comprised of a guide bar positioned adjacent one of the lay swords, means on the loom frame for adjusting said guide bar about a vertical axis into parallelism with the path of movement of said lay sword and for holding the guide bar in adjusted position, separate pieces having surfaces engaging respectively with opposite sides of said guide bar, and means securing said pieces to said lay sword for separate, independent adjustment laterally of the path of movement of the lay.
